INVENTOR.
William Klatzke
BY
John W. Goodman.
ATTORNEY.

UNITED STATES PATENT OFFICE.

WILLIAM KLATZKE, OF DETROIT, MICHIGAN.

RINGLESS PISTON.

Application filed June 30, 1923. Serial No. 648,772.

To all whom it may concern:

Be it known that I, WILLIAM KLATZKE, a citizen of the United States, and residing at Detroit, county of Wayne, and State of Michigan, have invented a new and Improved Ringless Piston, of which the following is a specification.

This invention relates to pistons for internal combustion engines, and has for its primary object the provision of a one-piece piston operable without the use of piston rings or other separable packing to closely press against the cylinder wall and prevent the leakage of the combustible gas around the piston during the operation of the engine.

Another object of the invention is the construction of an integral piston of substantially barrel shape with a solid reinforced head portion of slightly lesser diameter than the cylinder and a slotted body portion arranged with its waist of a diameter greater than the cylinder and then gradually tapering to its foot, which is of slightly lesser diameter than the cylinder.

A further object of the invention is the arrangement of a simple, light and easily formed piston which may be cast of any desired metal or alloy and quickly machined and slotted to snugly fit within the cylinder, the slots being arranged to permit automatic adjustment of the piston under varying temperature conditions.

The above and other objects will be apparent from the following description wherein reference is made to the accompanying drawings illustrating a preferred embodiment of the invention, and wherein similar reference numerals designate similar parts throughout the several views.

In the drawings, Fig. 1 is a perspective view of my improved piston.

Fig. 2 is a central horizontal section through the connection with the wrist pin of the connecting rod, and

Fig. 3 is a central vertical section taken substantially on the line 3-3 of Fig. 2 but with the wrist pin and connecting rod removed.

In the drawings, numeral 5 designates the head portion of the piston which, as best shown in Fig. 3, is of a substantial thickness and reinforced with ribs 6, herein shown as projecting radially from a central hub 7 arranged below the centering notch 8 wherefrom the piston is machined. The outer di-

ameter of the piston gradually tapers from the head portion 5 to the waist 9 which is preferably of a diameter .004 to .005 greater than the diameter of the cylinder wall. The 60 waist portion 9 is arranged substantially centrally of the longitudinal axis of the piston. From such waist the piston tapers in both directions, the head portion and foot portion 10 being both of substantially .002 65 smaller than the bore of the cylinder.

The piston is preferably cast in one-piece from grey iron or the like, though any desired metal or alloy can be used. It is not necessary however that tempered steel or 70 the like be used for resiliency, as the shape of the piston coupled with the arrangement of slots presently to be described give to practically all metals adapted for use as pistons a sufficient resiliency. The body portion of the piston is slotted longitudinally with a plurality of spaced slots 11 open at the foot portion 10 and extending to the ribbed portion of the head 5. (See Fig. 3.) The portion of the slots 11 below the waist 80 of the piston is wider than that above the waist by .001 or .002 inch. The portions between adjacent slots 11 are adapted to move toward and away from each other when the piston is inserted into the cylinder bore, the enlarged waist portion 9 engaging the cylinder wall and forcing the movable foot portions inwardly until the piston snugly fits within the cylinder. The solid head portion 5 is accordingly backed 90 by a resilient body portion with its center engaging the cylinder wall and gradually tapering therefrom to the foot portion which is clear of the cylinder. The piston thus rides with its center or waist portion 9 in 95 contact with the cylinder wall and is under tension sufficient to maintain this engagement at all times, whether the cylinder is cold or heated. One or more circumferential grooves 12 may be provided in the periphery of the piston adjacent the waist portion 9 to collect oil and aid in forming the oil-seal during the operation of the engine. Excess oil may escape to the interior of the piston through holes 13.

The piston is secured to the connecting rod 14 by means that permit the expansion and contraction of the piston relatively to the connecting rod. In the illustrated embodiment I have provided a pair of bosses 110 15 integrally formed with the piston and adapted to receive the wrist pin 16, which

is of slightly lesser diameter than the bore of the bosses. One extremity of the wrist pin is securely fastened to one of the bosses by means of the stud 17 or the like, while the opposite end of the wrist pin is free, permitting movement of the piston walls relatively thereto during the expansion and contraction. A bearing 18 carried by the connecting rod 14 surrounds the central portion of the wrist pin in the usual manner.

While it will be apparent that the illustrated embodiments of my invention herein disclosed are well calculated to adequately fulfill the object and advantages primarily stated, it is to be understood that the invention is susceptible to variation, modification and change within the spirit and scope of the subjoined claim.

Having described my invention, I claim:—

A piston formed integrally with head and foot portions of lesser diameter than the cylinder bore and a central waist portion of greater diameter than the cylinder bore and having a circumferential oil receiving groove in its periphery, the waist and foot portions being provided with a plurality of spaced slots extending longitudinally of the piston and open at their lower ends.

In witness whereof I hereunto set my hand.

WILLIAM KLATZKE.
